UNITED STATES PATENT OFFICE.

ALFRED J. SODEN, OF NEWARK, NEW JERSEY.

CAPPED PROJECTILE.

No. 918,923.

Specification of Letters Patent. Patented April 20, 1909.

Application filed March 17, 1908. Serial No. 421,698.

To all whom it may concern:

Be it known that I, ALFRED J. SODEN, a citizen of the United States, residing at Newark, in the county of Essex and State of New Jersey, have invented certain new and useful Improvements in Capped Projectiles; and I do hereby declare the following to be a full, clear, and exact description of the invention, such as will enable others skilled in the art to 10 which it appertains to make and use the same, reference being had to the accompanying drawings, and to the figures of reference marked thereon, which form a part of this specification.

15 This invention comprises a cap to be placed on the pointed end of a projectile, and also the particular method of applying the cap, whereby the cap is insured against accidental removal.

20 The invention comprises a projectile having a pointed end and having an annular groove in the pointed end, the groove acting to receive a split ring, and the split ring in turn having means coöperating with means 25 on the cap for adjusting the pressure on the ring to force it in the groove, and finally means for permanently securing the adjustable means in place.

The invention is further designed to apply 30 the force to seat the ring in the groove in a direction toward the point of the projectile, the point acting to co-act with the seating force, and in this way there is no slack afterward, such as is present when the ring is 35 forced in the groove and not toward the point. When the old method is used there is a chance for play when the seating pressure is relaxed.

The invention is illustrated in the accompanying drawing, in which—

Figure 1 is a section of a cap and a ring, and the pointed end of a projectile is shown broken away. Fig. 2 is a view of the cap and ring, and Fig. 3 is a small detail showing 45 a modified form of construction.

Any style of projectile can be used that has a pointed end 10 which is provided with an annular groove 11. A split ring 12 having a bead 13 to fit in the groove is placed in 50 the groove, the installation being permitted by reason of the splitting at 14. The split ring has on its exterior a thread 15 which is preferably tapered, and it is embraced by a thread 16 on the annular flange 17 on the end 55 of the cap 18. The cap 18 is recessed to fit the point 10, and when it is turned to screw

the threads together it bears on the point 10 and the pressure on the ring is therefore toward the point. This pressure, with the compression caused by the tapered screw, securely seats the bead 13 of the ring snugly in the groove of the shell, and there is no reaction of the parts possible when rotation of the cap ceases. This is contrary to those constructions where the compression on the binding element has been radial only or accompanied by a pressure away from the point. These old methods sometimes caused a slack when the pressure was relaxed at the completion of the operation, and an accidental displacement of the cap has happened.

To permit the screwing of the parts together I provide the ring 12 with a spanner hole or holes 19 and the cap with a spanner hole or holes 20. When spanner wrenches 75 are placed in these holes the parts can be screwed or unscrewed. To lock the parts together, when all the parts are assembled, I place a tool in the hole 20 and mutilate or flatten the thread 15 of the ring so that the 80 cap cannot be turned back to release the split ring.

An alternative construction is illustrated in Fig. 3, in which I employ a split ring 21 which is in turn inclosed by a solid ring 22 85 which receives the cap 18 as the ring 12. A beveled surface 23 throws the split ring 21 inward and toward the point when the cap is screwed home.

I do not confine myself to a screw connection between the ring and cap, since other means may be employed for securing them together.

Having thus described my invention, what I claim is:—

1. The combination of a shell having a pointed end and having an annular groove therein, with a split ring to be sprung in the groove, a cap bearing on the pointed end of the shell and on the ring, and an adjustable 100 operative connection between the cap and the ring to compress the ring in the groove.

2. The combination of a shell having a pointed end and having an annular groove therein, with a split ring to be sprung in the 105 groove, a cap bearing on the pointed end of the shell and on the ring, and an adjustable operative connection between the cap and the ring adapted to be rotated to cause the compression of the ring in the groove.

3. The combination of a shell having a pointed end and having an annular groove

therein, with a split ring to be sprung in the groove, a cap bearing on the pointed end of the shell and on the ring, and an operative connection between the ring and the cap adapted to draw the ring toward the point of the shell and compress it in the groove.

4. The combination of a shell having a pointed end and having an annular groove therein, with a split ring in the groove, a cap bearing on the pointed end of the shell, and an operative connection between the cap and the ring to cause an adjustable pressure on the ring, the operative connection between the cap and the ring being adapted to be de-
10 formed to permanently secure the cap and the ring together.

5. The combination of a shell having a pointed end and having an annular groove therein, with a split ring in the groove having a tapered portion, a cap bearing on the point of the shell and having a tapered portion to engage the tapered portion of the ring, and means for forcing the tapered portions together to compress the ring in the groove.

25 6. The combination of a shell having a pointed end and having an annular groove therein, with a split ring in the groove having a tapered portion, a cap bearing on the point of the shell and having a tapered portion to engage the tapered portion of the ring, and means for forcing the tapered portions together to compress the ring in the groove and draw the ring toward the point of the shell.

7. The combination of a shell having a pointed end and having an annular groove therein, with a split ring in the groove having a screw-thread on its exterior, and a cap bearing on the pointed end of the shell and having a screw-thread to engage the thread on the ring to lock the parts together; the

threads on the ring being adapted to be deformed to permanently secure them together.

8. The combination of a shell having a pointed end and having an annular groove therein, with a split ring in the groove having a screw-thread on its exterior, a cap bearing on the pointed end of the shell and having a screw-thread to engage the thread on the ring to lock the parts together, and means for holding the ring against rotation, the cap having spanner holes for permitting its rotation, the spanner holes permitting the insertion of a tool for mutilating the thread on the ring.

20 9. The combination of a shell having a pointed end, with a split ring, the pointed end of the shell and the split ring having co-acting means to prevent the withdrawal of the split ring when the split ring is compressed, a cap bearing on the pointed end of the shell and on the ring, and an adjustable operative connection between the cap and the ring to compress the ring.

25 10. The combination of a shell having a pointed end with a split ring, the split ring and the pointed end of the shell having co-acting means for preventing the withdrawal of the ring when the ring is compressed, a cap bearing on the pointed end of the shell and on the ring, and an operative connection between the ring and the cap adapted to compress the ring against the shell and draw the ring toward the point of the shell.

In testimony that I claim the foregoing, I have hereunto set my hand this 16th day of March 1908.

ALFRED J. SODEN.
